STARTING APPARATUS FOR ELECTRIC
DISCHARGE DEVICESLeroy J. Buttolph, Grantwood, N. J., assignor to
General Electric Vapor Lamp Company, Hoboken, N. J., a corporation of New Jersey

Application April 29, 1929, Serial No. 359,125

7 Claims. (Cl. 176—124)

The present invention relates to gaseous discharge devices, and particularly to those devices of this type which are designed to operate with a hot cathode.

5 The particular object of the invention is to improve the starting and operation of such devices, but other objects and advantages will be apparent from the following detailed description of two forms of apparatus embodying my invention or 10 from an inspection of the accompanying drawing.

The invention consists in certain new and novel features of construction and combinations of parts hereinafter set forth and claimed.

Gas or vapor discharge devices of low voltage 15 type are commonly provided with means for impressing a high voltage surge of short duration upon one of their electrodes in order to initiate a discharge when starting, and also in some cases have means for heating the cathode in order to 20 facilitate starting. In such cases the application of the high potential to the electrodes before the cathode has had time to heat up is injurious, as, if a discharge is started before the cathode has 25 reached the proper temperature for free emission of electrons, the discharge is confined to one spot on the cathode, and tends to disintegrate the electron emitting material. The present invention is for an apparatus to delay the initial application of the high potential until the cathode has 30 reached the operating temperature. By using the cathode itself to produce the delay the exact lag necessary is obtained regardless of ambient temperature, or any other variable conditions.

In the accompanying drawing there is shown 35 for purposes of illustration one form of apparatus embodying the invention, together with a modification thereof, in which

Fig. 1 is a schematic diagram of a gaseous discharge device partly in section, and its connection 40 to the associated apparatus,

Fig. 2 is an end view of the cathode shown in Fig. 1,

Fig. 3 is a sectional view taken along the line 3—3 of Fig. 2,

Fig. 4 is a side view of an alternative cathode structure,

Fig. 5 is a face view of the structure of Fig. 4 with the front plate removed, and

Fig. 6 is an enlarged sectional view taken along 50 the line 6—6 of Fig. 5.

In the drawing an envelope 1 of glass or the like, which contains any desired gas, such as neon, or source of vapor, such as mercury, or combinations thereof, has sealed therein at one end the 55 anodes 2 of iron or other suitable metal. At the

opposite end of said envelope 1 is the cathode 3 which is formed either from a bimetallic strip wound in the form of a helix with the turns lying in close proximity to each other, or from a bimetallic cylinder having a helical slot cut therein. 60 The exterior metal of the cathode is preferably one, such as nickel, which will freely yield electrons when heated. The surface thereof is also preferably coated with alkaline or alkaline earth oxides to increase the electronic emissivity. The 65 inner end of said cathode 3 is rigidly supported by the inlead 4, which is sealed through the end of the envelope 1. At the opposite end said cathode 3 is loosely supported by a porcelain bushing 5 which is mounted upon a rigid inlead 6, being 70 held in position thereon in any suitable manner, as by the cross wires 6' welded thereto. A metallic bridge 7 is welded across the interior end of the cathode 3, and serves as a lead and support for one end of a centrally disposed filament 8 of 75 tungsten or other suitable material. The other end of said filament 8 is welded to the end of the inlead 6 adjacent to the bushing 5. The free end of the cathode 3 is bent outwardly and carries a contact 9. Another rigid inlead 10 terminates 80 in a contact 11 which is so located as to cooperate with the contact 9 when said contact 9 reaches the position occupied by it when the cathode 3 is at operating temperature.

An auto-transformer 15 is connected by leads 85 16 and 17 to a suitable source of alternating current. The end leads of said auto-transformer 15 are each connected through a resistance 18 to one of the anodes 2 through the leads 19. A mid-point of the transformer 15 is connected 90 through an iron cored inductance 20 to the inlead 4 of the gaseous discharge device. One terminal of a low voltage secondary 21 is likewise connected to the inlead 4, while the other terminal thereof is connected to the inlead 6. A connection 95 is likewise made from the inlead 10 to one terminal of a mercury switch 22, of the type commonly called a shifter. The other terminal of said shifter 22 is connected through a resistance 23 to one of the leads 19. Said shifter 22 (which 100 is only schematically shown) is normally in a circuit closing position, but has an armature in electromagnetic relation to the core of inductance 20, so that when current flows through said inductance 20, said armature is attracted to said 105 core and rotates said shifter to an open circuit position.

In the operation of this device an alternating potential is applied to the leads 16 and 17, whereupon current immediately starts to flow from the 110

secondary 21 through inlead 4 to cathode 3, thence by bridge 7 to filament 8 and through inlead 6 back to said secondary 21. Normal operating potential is likewise impressed between each of the anodes and the cathode but is insufficient to initiate the discharge. The current passing through the filament 8 heats up the cathode 3, causing the lower end thereof to rotate because of its bimetallic construction, carrying the contact 9 toward the contact 11. When the cathode reaches its operating temperature the contact 9 is moved into engagement with said contact 11, completing the circuit from the mid-point of transformer 15 through inductance 20, inlead 4, cathode 3, contact 9, contact 11, inlead 10, shifter 22, resistance 23, part of a lead 19 and a resistance 18 back to one of the ends of transformer 15. Current thereupon flows through said circuit, building up a strong magnetic field about the inductance 20. As said inductance 20 thus stores up energy its core becomes magnetized, attracting the armature of shifter 22, whereby the circuit is opened. As the magnetic field about said inductance 20 collapses a high voltage surge is impressed upon the cathode 3, which tends to initiate a discharge to one of said anodes 2. If, for any reason, a discharge is not started the shifter 22 again closes the circuit after the inductance 20 has become demagnetized and the cycle is repeated until a discharge occurs, the discharge current then keeping shifter 22 in an open circuit position. Once a discharge is started it will be maintained by the potential difference existing between each of said anodes and said cathode. Since the cathode itself is used to determine the first application of the high voltage surge it is obvious that the starting of the device will always occur at the proper time, regardless of variable atmospheric temperature, the temperature of the cathode when the filament is energized, or any other variable factors.

In Figs. 4-6 there is shown a different form of cathode which is interchangeable in the circuit shown in Fig. 1 with the cathode previously described. An insulating member 25 somewhat rectangular in form and having a rectangular opening therein has attached to either face the bimetallic cathode plates 26 and 27, each of said plates being slightly narrower than the opening in the insulating member 25. The insulating member 25 is supported on rigid inleads 4 and 6 which pass through one of the short sides of said insulating member. Inlead 4 is connected to the cathode plate 26 by the lead 28. A filament 29 is attached to the end of inlead 4 at one end and to the inlead 6 at the other end, its midpoint being supported at the opposite end of the opening in the insulating member 25. The cathode plate 27 is connected to the inlead 10. Centrally located on the inner side of the cathode plate 26 is a contact 30, and correspondingly located on the plate 27 is a contact 31 which makes contact with said contact 30 when the plates 26, 27 approach each other. Each of said cathode plates 26, 27, which may be of the same composition as the cathode 3 of Figs. 1-3, is curved slightly outward when cold, and has the material with the greatest coefficient of expansion on the inner side. As the plates 26, 27 heat up under the influence of the filament 29 they will tend to bend inwardly, but since they are biased in the opposite direction this tendency results only in potential energy which is stored up in the form of internal stresses until the plates

finally snap through their center line and bring the contacts 30, 31 together, in a manner well known in the art. When this occurs cathode plate 27 is so connected as to serve as a cathode during the operation of the device, and a circuit is made through inlead 4, lead 28, cathode plate 26, contact 30, contact 31, cathode plate 27, and inlead 10 which corresponds to the circuit made from inlead 4 to inlead 10 in Fig. 1 by the closing of the contacts 9 and 11. On cooling of the cathode structure the contacts 30, 31 are snapped apart after a time interval. This structure offers the obvious advantages of the snap action in making and breaking the shifter circuit. It is to be understood that the structures shown and described are for purposes of illustration only, and that the invention can be embodied in other forms without departing from the spirit thereof. It will be obvious that expansion of the cathode structure can be availed of in many ways to accomplish the same result, and that while shown in connection with an alternating current device the invention is equally applicable to a direct current device.

I claim:

1. In combination, a gaseous discharge device having a cathode of refractory solid material adapted to give off electrons when heated, means for heating said cathode, means for initiating a discharge within said device and means responsive to temperature changes in said cathode for delaying the operation of said means for initiating a discharge until said cathode has reached an operating temperature.

2. In combination, a gaseous discharge device having a cathode of refractory solid material adapted to give off electrons when heated, means for heating said cathode, means for applying a voltage surge to said discharge device, and means responsive to temperature changes in said cathode for delaying said voltage surge until said cathode has reached an operating temperature.

3. In combination, a gaseous discharge device having a cathode of refractory solid material adapted to give off electrons when heated, means for heating said cathode, means for initiating a discharge within said device and means responsive to thermal expansion of said cathode to delay the operation of said means for initiating a discharge until said cathode has reached an operating temperature.

4. In combination, a gaseous discharge device having a cathode adapted to give off electrons when heated, means for heating said cathode, means for applying a voltage surge to said discharge device, said last mentioned means including an element responsive to thermal expansion of said cathode to control energization of said surge applying means.

5. In combination, a gaseous discharge device having a cathode of refractory solid material adapted to emit electrons when heated, means for heating said cathode, means to initiate a discharge through said device, said last mentioned means being normally inoperative, and means operated by thermal expansion of said cathode to render said discharge initiating means operative when said cathode has reached a temperature at which the free electron emission therefrom will support the normal discharge current.

6. In combination, a gaseous discharge device having a cathode adapted to emit electrons when heated, means for heating said cathode, means for applying a voltage surge to said device, said means being normally inoperative, and means

operated by thermal expansion of said cathode to render said means for applying a voltage surge operative.

7. In combination, a gaseous discharge device having a cathode of refractory solid material adapted to give off electrons when heated, means for heating said cathode, means for initiating a discharge within said device, and means respon-

sive to temperature changes in said cathode for delaying the operation of said means for initiating a discharge until said cathode has reached a temperature at which the free electron emission therefrom will support the normal discharge 80 current.
